CLAIM

The ornamental design for a monitor stand as shown and described.

DESCRIPTION

FIG. 1 is a front, right and top perspective view of a monitor stand, showing my design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is rear, left side and top perspective view thereof, shown in a usable state.

The broken lines depict portions of the monitor stand that form no part of the claimed design.
